TWO-CYCLE GASOLINE ENGINE

Garland E. Lyvers, Racine, Wis.

Application January 22, 1957, Serial No. 635,439

5 Claims. (Cl. 123—65)

This invention relates to a two-cycle gasoline engine, and, more particularly, it relates to a two-cycle gasoline engine wherein the gasoline and oil are not mixed, and the engine has means for improving the charging thereof.

In the modern-day two-cycle gasoline engine, it is common practice to mix lubricating oil with the gasoline in order that the moving parts of the engine be properly lubricated. Of course, this results in a relatively inefficient engine, since the oil enters the combustion chamber, and the spark plugs eventually become fouled. It is, therefore, a primary object of this invention to provide a two-cycle gasoline engine wherein the oil need not be mixed with the gasoline. In accomplishing this object, the engine operates at a high efficiency, and the spark plug is less likely to become fouled. Nevertheless, the engine is properly lubricated in the usual manner of lubricating a four-cycle engine.

It is another object of this invention to provide a two-cycle gasoline engine wherein the air charging and exhaust steps are performed in an improved manner.

Still another object of this invention is to provide a two-cycle engine which does not get too hot, particularly in the wrist pin and piston parts.

Other objects and advantages will become apparent upon reading the following description in conjunction with the accompanying drawings, wherein:

Fig. 1 is a sectional view of a fragment of a preferred embodiment of this invention.

Fig. 2 is a sectional view taken on the line 2—2 of Fig. 1.

Fig. 3 is an end view of a fragment of Fig. 1.

Fig. 4 is a fragment of Fig. 1, but showing a variation of parts.

Fig. 5 is a fragment of Fig. 1, but showing a variation of parts.

Fig. 6 is a sectional view taken on the line 6—6 of Fig. 5.

Similar reference numerals refer to similar parts among the several views.

The drawings show a fragment of a two-cycle single cylinder gasoline engine including a conventional crank case 10 onto which is suitably bolted a cylinder 11. A crank shaft 12 is rotatably mounted within the crank case 10, and the crank shaft includes the usual eccentric portion 13. The connecting rod 14 is suitably attached to the crank case portion 13 to rotate on the latter, and the connecting rod 14 extends from the crank shaft to the wrist pin 16 which is shown to include an insert 17, and, of course, the end of the connecting rod 14 encircles the wrist pin 16 while a suitable bushing is disposed between the connecting rod and the pin 16. The wrist pin 16 passes through a main piston 18 which is disposed within the cylinder 11 in the usual manner. Thus, upon reciprocation of the piston 18 within the cylinder 11, the crank shaft 12 will be rotated, all in the well-known manner of operation of a gasoline engine.

The important feature of this invention resides in the

2

design and construction of the main piston. It will be seen that the piston 18 is provided in the skirt 19 with two bores or cylinders 21, each of which receives a piston 22. Generally, the pistons 22 each having a connecting rod 23 attached thereto with the two rods being mounted on an eccentric 25 integral with the crank shaft 12, as shown, for rotation with the crank shaft. Thus, the two rods 23 and the pistons 22 are shown in Fig. 1 to be reciprocable in directions opposite to the movement of the piston 18 for a reason which will be apparent later. It is preferred that the stroke of the pistons 22 be at least one half of the length of stroke of the piston 18. The usual wrist pins 24 are provided at the upper ends of the rods 23 to attach the rods to the pistons 22, and also it is preferred that suitable bushings be provided between the rods 23 and the eccentrics 25 on the crank shaft 12. It will be seen that the bores or cylinders 21 extend from the bottom edge of the piston skirt 19 to the openings 26 and 27 in the piston 18 immediately below the main piston wrist pin 16. Also, the wrist pin 16 is provided with openings 28 and 29 which respectively align with the openings 26 and 27, and also the wrist pin core 17 is provided with a passageway 31 in direct communication with the openings just mentioned. At this time it should be mentioned that the engine is in the bottom center position, and also the openings just described are always in the aligned position as shown and are always in communication with the passageway 31 in the wrist pin.

With the foregoing described arrangement, when the piston 18 is reciprocated, the pistons 22 reciprocate to always move in the direction opposite to that of the piston 18, and thus all of the openings and passageways of the piston 18 which are above the tops of the pistons 22 become the working chambers for the purpose of charging the cylinder 11 with the necessary air and gas for operation of the engine. It should thus be understood that the air is not drawn from the crank case 10, as in the customary arrangement of a two-cycle gasoline engine.

When the piston 18 is moved from the bottom center position shown toward the top center position, the pistons 22 move downwardly, and air or air and gasoline mixture is thus drawn into the passageways and openings above the top edges of the pistons 22 to fill the space then vacated by the piston 18. Conversely, when the spark plug fires, and the piston 18 is forced downwardly from the top center position mentioned back to the bottom center position shown, air in the opening and passageways is forced therefrom and through the side port and into the cylinder 11 above the piston 18. Of course, along with this charge of air introduced into the passageways and openings, the necessary charge of gasoline will enter the cylinder through the carburetor shown.

The important advantage of this arrangement is that the oil which would be in the crank case 10 is not mixed with the air entering the cylinder 11 since the air is not taken from the crank case, as in the popular manner of operating a two-cycle engine. Instead, the oil in the crank case 10 is sealed from entering the cylinder 11 above the piston 18 by the oil ring 32 on the piston 18 and the oil rings 33 on the pistons 22. Also, the usual compression rings 34 are provided on the pistons 22, and two compression rings 36 are shown on the piston 18.

The cylinder 11 is provided with an inlet port 37 and an exhaust port 38 with the two ports in offset position across the cylinder as shown. Thus, in the usual arrangement, as the piston moves downwardly from top center to bottom center, the exhaust port 38 is first uncovered by the piston, and then the inlet port 37 is uncovered, and, of course, this permits the expended gases to escape through the exhaust slightly before the inlet port is uncovered by the downwardly moving piston 18.

Of course, the inlet port 37 is in communication with the passageway 31 in the wrist pin 16, and thus the air which is compressed below the top of the piston 18 upon downward movement of the latter will move from the passageway 31 and through the port 37 and into the cylinder 11 above the top of the piston 18.

A conventional carburetor 39 is attached to the side of the cylinder on a plate 41 which is suitably attached to the cylinder to enclose the inlet port 37. Of course, the gasoline moves through the carburetor 39 when the air is entering the cylinder 11, and a check valve 42 is shown disposed over the opening leading from the carburetor to the port 37, and thus the valve 42 prevents the air and gasoline mixture from going back into the carburetor. Of course, after the air and gasoline mixture have been injected into the cylinder 11, the piston 18 moves upwardly to close the port 37 and finally close the port 38, and continuous upward movement of the piston 18 causes the gas and air mixture to be compressed in the cylinder 11 and, therefore, prepared for firing.

An advantage of the arrangement described with respect to the piston 18 and the ports in the cylinder 11 is that the charging air passing into the cylinder through the port 37 comes from a point which is immediately adjacent the inlet port 37. In other words, the charge of air is not drawn or forced in from the crank case 10 which is generally disposed a greater distance from the inlet port on the cylinder. Thus, the inlet air is better compressed, and released into the cylinder at the most advantageous time. Also, air drawn into the passageway 31 keeps the wrist pin, cylinder, piston, and all other adjacent parts cool to avoid overheating of the engine and simplify cooling the engine. At the same time, the mixture entering the cylinder will be pre-heated, as desired.

Fig. 4 shows an alternative arrangement of mounting the connecting rods 23 for the small pistons 22. In this arrangement, the rods 23 are modified in form to the shown rod 45 and are stationarily mounted by means of a stud or support 43 which is anchored in the crank case 10 and connected to the rod 45 to maintain the latter in a fixed position. With this arrangement, of course, there would be two connecting rods 45 which are stationary, and then also the pistons 22 are stationary, and the main piston 18 reciprocates up and down over the pistons 22. Air and gasoline would then be drawn into the cylinder 11 above the top of the pistons 22, and the air and the gasoline are also charged into the cylinder when the main piston 18 moves to the bottom center position. Since the rods 45 are thus maintained in a fixed position, the rods have no throw and, therefore, the attending problems with regard to connecting rod throw do not arise.

Figs. 5 and 6 show another arrangement of mounting and maneuvering the connecting rod 23. In this instance, Figs. 5 and 6 show the pistons 22 to be provided with two pins 44 and 46, which pass through the pistons 22 and through the connecting rods 47 which are comparable to the rods 23. With the rods 47 attached to the pistons 22 in the manner shown, the rods 47 remain on a line along the axes of the rods. Thus, the rods have no throw. The lower end of each of the rods attaches to a stud 48 which is shown provided with ball bearings 49, and the stud 48 projects between an inner race 51 and an outer race 52. The races and projecting end of the stud are disposed within the counter-weight 53 which is formed on the crank shaft to rotate therewith. It will also be noted that the bearing has a ring 54 integral therewith, and the ring encircles the ball bearing races, as best shown in Fig. 5. With the arrangement shown in Figs. 5 and 6, rotation of the crank shaft causes the counter-weight to rotate therewith, but since the ring 54 and stud 48 are related to the counter-weight 53 through the ball bearings 49, the stud 48 and the ring 54 do not rotate with the counter-weight 53. Of course, it will further be noted that the ball bearings and the races 52 and 51 are eccentric with respect to the crank shaft, and, therefore, rota-

tion of the latter causes the races to move in an eccentric path. The eccentric movement in turn causes each of the connecting rods 47 to move in a purely axial direction; that is, in this instance, up and down with the rods 5 having no throw. Here also, it will be noted that the eccentricity of the ball bearing is opposite to that of the crank shaft and, therefore, as the crank shaft goes down, the ball bearings go up, and also the reverse action occurs.

While a specific embodiment of this invention has been shown and described, it should be understood that certain changes could be made in the embodiment and, therefore, the invention should be limited only by the scope of the appended claims.

What is claimed is:

15. In a two-cycle gasoline engine, the combination comprising an engine cylinder, a first piston reciprocably disposed within said cylinder and including a skirt portion, a crank case attached to said cylinder, a crank shaft rotatably mounted within said crank case, a wrist pin attached to said first piston at the top of the latter and extending diametrically thereacross, a connecting rod attached between said crank shaft and said wrist pin of said first piston for rotation of said crank shaft upon reciprocation of said first piston, said first piston having a bore in said skirt portion thereof, a second piston disposed within said bore reciprocable therewithin, said wrist pin having an air passageway in communication with and above said bore and opening to the side of said cylinder, said cylinder having a port in communication with said passageway at the bottom center position of said first piston and extending to said cylinder at a location above said top of said first piston when the latter is in said bottom center position, and a rod attached to said second piston for causing said pistons to be relatively movable.
20. In a two-cycle gasoline engine comprising in combination a cylinder having an air intake port in one side thereof, a crank case attached to said cylinder, a crank shaft rotatably mounted in said crank case, a main piston reciprocably disposed in said cylinder for movement over said intake port to a bottom position where the top of said piston is below the top of said intake port and said piston including a wrist pin having an air passageway in communication with said port during the bottom portion of the stroke of said main piston and including a skirt portion with two bores therein in communication with said passageway and disposed below the latter, a connecting rod attached between said main piston and said crank shaft, an intake air piston movably disposed in each said bore, and a connecting rod attached between each said intake air piston and said crank shaft for reciprocation relative to that of said main piston to cause air to enter said cylinder through said intake port.
25. In a two-cycle gasoline engine, the combination comprising an engine cylinder having an air inlet port and an exhaust port, a main piston reciprocably disposed within said cylinder and including a skirt portion having two bores therein disposed parallel to said cylinder, a crank case, a crank shaft rotatably mounted within said crank case, a connecting rod attached between said crank shaft and said main piston for rotation of said crank shaft upon reciprocation of said main piston, a secondary piston disposed within each of said bores and relatively movable therewithin, said main piston having an air passageway in communication with and above said bores and in communication with said inlet port of said cylinder when said piston is in a bottom position.
30. In a two-cycle gasoline engine, the combination comprising an engine cylinder having an inlet port in the side thereof, a first piston reciprocably disposed within said cylinder and including a skirt portion with a bore therein, a crank case attached to said cylinder, a crank shaft rotatably mounted within said crank case and including two oppositely disposed eccentrics rotatable with said crank shaft, a connecting rod attached between one of said eccentrics on said crank shaft and said first piston

for rotation of said crank shaft upon reciprocation of said first piston, a second piston disposed within said bore and reciprocable therewithin, a second connecting rod attached between the other of said eccentrics and said second piston for reciprocation of said second piston in the direction opposite to that of said first piston when the latter is adjacent the bottom of its stroke, a wrist pin connected to said first piston and having an air passageway in communication with and above said bore and opening to the side of said cylinder for communication with said inlet port at said bottom of the stroke of said first piston.

5. In a two-cycle gasoline engine, the combination comprising an engine cylinder, a piston reciprocably disposed in said cylinder and including a skirt portion, a crank case attached to said cylinder, a crank shaft rotatably mounted within said crank case, a wrist pin attached to said piston at the top thereof above said skirt portion and extending diametrically thereacross, a connecting rod attached between said crank shaft and said wrist pin for rotation of said crank shaft upon reciprocation of said piston, said piston having a bore in the skirt portion thereof and said bore being open to said crank case, said wrist pin having an opening through the side thereof

5

10

20

toward the piston bottom position, said wrist pin having an air passageway in communication with said opening and extending to one side of said cylinder, said cylinder having a port in full flow communication with said passageway at the bottom position of said piston during a length of the stroke, and said port being in direct flow communication with said cylinder above the top of said piston when the latter is in said bottom center position.
